UNITED STATES PATENT OFFICE

2,443,563

AUTOMATIC ELEVATOR

Albert E. Jackson, Columbus, Ind.

Application March 3, 1947; Serial No. 731,987

6 Claims. (Cl. 214—99)

1

The present invention relates to an automatic elevator, or more accurately, to a device for automatically transporting weights, successively, from an elevated point to a lower point. The primary object of the invention is to provide a device including a car, which, when raised to an elevated position, and loaded with a weight, will travel to a lower station, there automatically discharging its weight, then return to the upper station, where another weight will be automatically fed to the car, and so on, continuously, so long as the supply of weights is maintained at the upper station. A further object of the invention is to provide such a device in which the descent of the weighted car is utilized to impart to an inertia member a momentum sufficient to return the car, unweighted, from the lower station to the upper station; and in which the direction of rotation of the inertia member is reversed each time the car attains the upper station, but continues throughout the descent of the car and the subsequent ascent thereof. A further object of the invention is to provide novel means for feeding weights to the car at the upper station and for discharging such weights from the car at the lower station, the entire operation being automatic so long as the supply of weights is maintained at the upper station.

While the invention finds its primary utility as a toy, and is so illustrated and will be so described, it will be apparent to those skilled in the art that, should it be desired to transport weights from an upper floor in a factory, one at a time, to a lower floor, the principle underlying the present invention would be applicable to the solution of such a problem.

Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a front elevational view of an embodiment of my invention;

Fig. 2 is a fragmental perspective view, upon an enlarged scale, of the upper end of the said embodiment;

Fig. 3 is a fragmental perspective view of the lower end thereof;

Fig. 4 is a fragmental side elevation of the

weight-feeding means utilized in the illustrated embodiment of the invention; and

Fig. 5 is a similar view of the weight-discharging means utilized in the illustrated embodiment of the invention.

While the underlying principle of my invention may be variously embodied, I have illustrated herein a tower-like frame, indicated generally by the reference numeral 10, and comprising a plurality (in this case 4) of legs or pillars 11 converging upwardly and connected at their upper ends by a platform 12 and near their lower ends by a platform 13. Suitably secured, as by spot welding, to the platform 12 is a U-shaped bracket 14 having parallel, upstanding ears 15 and 16 provided near their upper ends with bearings 17 for the ends 18, 19 of an axle 19. In the illustrated embodiment of the invention, the bearings 17 are merely pressed sockets in the sheet metal ears 15 and 16, and the axle ends 18, 19 are tapered for reception in said sockets. The axle ends may be entered in said sockets by spreading the upper ends of the ears, whereafter the inherent resiliency of the sheet metal bracket 14 will return the ears to substantial parallelism, thus retaining the axle ends in said sockets. Obviously, in an industrial embodiment of the invention, more substantial bearing means for the axle 19 would be provided.

30 An inertia element is operatively associated with the axle 19. In the illustrated embodiment of the invention, said element comprises a flywheel disc 20 fixed to said axle. One end of a flexible strand 21, which, in the illustrated embodiment of the invention may be a simple cord or string, but which, in an industrial embodiment of the invention would be a wire cable, or the like, is suitably anchored to the axle 19, and said strand is adapted to be wound upon said axle in either of two opposite directions. Said strand extends through registering apertures 22 in the base of the bracket 14 and in the platform 12; and a car 23 is suspended from the opposite end of said strand. The length of the strand 21 is such that, when it is completely unwound from the axle 19, the car 23 will be positioned just above the platform 13.

In the illustrated embodiment of the invention, the floor of the car 23 is formed with an aperture 24 therein, the diameter of said aperture being slightly less than the diameter of each of a series of balls 25 so that, when one of those balls is introduced into the car it will come to rest with one of its minor circles supported upon 50 the periphery of the aperture 24, in the manner

particularly illustrated in Figs. 1 and 5, and will there be retained during descent of the car.

One means for guiding the car in its reciprocating movement is illustrated herein, and may comprise aligned perforations 26 in the top and bottom walls of the car 23 and on opposite sides thereof, together with a wire 27 whose opposite ends are threaded through suitable spaced openings in the base of the bracket 14 and the platform 12, so that the bight 28 is supported upon said bracket base, while the wire ends are led downwardly, in vertical parallelism, to be anchored upon ring bolts 30, or the like, fixed to the platform 13.

Near the upper end of the frame, I provide a trough or trackway 31, fixed to the legs 11, and inclining downwardly and inwardly toward the path of the car 23. At its lower end, I provide stop means comprising a pair of lips 32, 32 inclined upwardly and so disposed in the path of balls 25 received in the trough as to hold the same against downward movement. The lips 32, 32 are separated by a slot 33 so proportioned and designed that it extends rearwardly beyond the center of gravity of a ball resting against said lips. Projecting outwardly and upwardly from that edge of the bottom wall of the car 23 adjacent the lips 32 is a finger 34 so proportioned and designed that, as the car 23 approaches the upper limit of its path, said finger will engage a ball resting against the lips 32, at a point beyond the center of gravity of said ball, and will lift the same over the lips 32, in the manner illustrated in Fig. 4. It will be clear from an inspection of the drawings that the inclination of the finger 34 is such that, when such a ball 25 is lifted above the lips 32, it will be guided by the finger 34 to roll downwardly and into the aperture 24.

A tongue or finger 35 is struck up from the material of the platform 13 and projects vertically upwardly therefrom. Said tongue is so positioned that, when the car, carrying a ball, approaches the lower limit of its path the upper end of the tongue 35 will strike the ball at a point on the opposite side of the center of gravity of said ball from the finger 34 to arrest downward movement of the ball so that, as the car continues to descend, the ball will be urged toward the finger 34 and will be discharged from the car.

From the above description of structure, the operation of the illustrated device will be clear. One or more balls 25 being charged into the receptacle 31, the axle 19 will be rotated, in either direction, to wind the strand 21 thereon, thereby elevating the car 23. As the finger 34 engages the lowermost ball in the receptacle 31 to lift the same over the lips 32, that ball will be fed into the car 23, and will find a seat upon the periphery of the aperture 24. Now, if the spindle is released, the combined weight of the car and the ball carried therein will cause the car 23 to descend, thus unwinding the strand 21 and causing rotation of the axle and its inertia element 20 in, for instance, a counter-clockwise direction, as viewed in Fig. 1. The mass and distribution of the inertia element 20 are so related to the length of the path of the car 23 and the combined weight of said car and the ball 25 that descent of the car from the feeding station to the discharging station will impart to the inertia element a momentum sufficient to return the unloaded car to the feeding station. Thus, as the car 23 nears the lowermost end of its path, the ball 25 strikes the tongue 35 and is discharged from the car. As has been said, the length of the

strand 21 is such that it will be completely unwound from the axle 19 just before the car 23 reaches the platform 13.

Under the influence of the momentum imparted to the inertia element 20 by descent of the car 23 and the consequent unwinding of the strand 21, said inertia element will continue to spin, in the said counter-clockwise direction, whereby the strand 21 will be rewound upon the axle 19 but in the opposite direction. Thereby, the car 23, having been unloaded, will be elevated; and, as has been said, the parts are so designed and proportioned that the momentum of the element 20 is sufficient to return the car 23 to its starting point. As said car nears the upper limit of its path, the finger 34 will engage the next successive ball 25 in the receptacle 31, which, of course, has moved down into engagement with the lips 32 upon removal of the first ball; and said finger will lift such next succeeding ball over the lips 32 and into the car 23, whereupon the cycle will be repeated, the element 20 spinning in a clockwise direction, this time, to permit the cable 21 to be unwound, and then to be rewound into its initial association with the axle.

This operation will be continuously repeated so long as the receptacle 31 is kept charged with weights of the proper character.

I claim as my invention:

1. In a device of the class described, an inertia element journalled for rotation upon an elevated axis, a car, means cooperating with said car to guide the same upon a path between two points at different elevations, means providing an operative connection between said car and said element whereby said element is driven as said car descends and the momentum of said element thereupon tends to elevate said car, means for increasing the effective weight of said car as said car nears the upper of said two points, comprising an inclined trackway mounted adjacent said upper point and inclined downwardly and toward said path, rollable members arranged in file formation in said trackway, means at the lower end of said trackway for retaining said members, and means on said car operable, as said car approaches said upper point, to transfer that member currently nearest said lower end of said trackway from said trackway to said car, and means to decrease the effective weight of said car as said car nears the lower of said two points, comprising a floor in said car, means for normally retaining a rollable member in said car on said floor, abutment means arranged adjacent the lower of said two points and cooperable with said retaining means, as said car nears said lower point, to release said element and cause the same to be discharged from said car.

2. The device of claim 1 in which said car floor is provided with an aperture adapted to receive and normally retain such rollable member, and in which said abutment means is arranged in registry with said aperture and engages such rollable member, as said car approaches said lower point, to eject such member from said car.

3. In a device of the class described, an axle, an inertia wheel fixed to said axle, means for supporting said axle for rotation upon an elevated, substantially horizontal axis, a flexible strand having one end anchored on said axle and adapted to be wound thereon, a weight-carrying car suspended on said strand and movable between upper and lower stations, means adjacent said upper station for automatically loading a weight upon said car as said car approaches said

upper station, and means adjacent said lower station for automatically relieving said car of a carried weight as said car approaches said lower station, the effective length of said strand being substantially equal to the distance from said axle to said lower station, and said loading means comprising a storage receptacle for weights, said receptacle having a lower end and a higher end, said lower end being provided with a divided stop comprising two lips separated by a slot, said slot extending rearwardly beyond the center of gravity of a weight resting against said lips, and a finger carried on said car and operable, as said car approaches said upper station, to enter between said lips, engage said weight beyond its center of gravity, and lift the same over said lips to deposit the same in said car.

4. In a device of the class described, an axle, means supporting said axle for rotation upon an elevated horizontal axis, a flexible strand having one end anchored on said axle and adapted to be wound upon said axle in either of two opposite directions a car secured to the other end of said strand and movable up and down toward and away from said axle when said strand is wound upon and unwound from said axle, a plurality of weights adapted to be successively placed on said car and removed therefrom near the upper and lower limits of the path of said car, respectively, and inertia means associated with said axle, the mass and distribution of said inertia means being so related to the length of the path of said car and the combined weight of said car and any one of said weights that the momentum impressed upon said inertia means by descent of said car carrying a weight from an elevated starting point to a nadir at the limit of the length of said strand will be sufficient to rewind said strand upon said axle to lift said car alone to such starting point.

5. In a device of the class described, an inertia element journaled for rotation upon an elevated axis, a car, means cooperating with said car to guide the same upon a path between two points at different elevations, means providing an operative connection between said car and said element whereby said element is driven as said car descends and the momentum of said element thereupon tends to elevate said car,

means for increasing the effective weight of said car as said car nears the upper of said two points and means to decrease the effective weight of said car as said car nears the lower of said two points, said weight-decreasing means comprising a floor in said car provided with an aperture adapted to receive and normally retain a rollable member, and an abutment means arranged adjacent the lower of said two points in registry with said aperture, said abutment means engaging such member, as said car approaches said lower point, to eject such member from said car.

6. In a device of the class described, a frame, a weight-carrying car mounted and guided for vertical reciprocation in said frame between upper and lower stations, means adjacent said upper station for automatically loading a weight upon said car as said car approaches said upper station, means adjacent said lower station for automatically relieving said car of a carried weight as said car approaches said lower station, and means for elevating said car when it is so relieved, said loading means comprising a storage receptacle for weights, said receptacle having a lower end and a higher end, said lower end being provided with a divided stop comprising two lips separated by a slot, said slot extending rearwardly beyond the center of gravity of a weight resting against said lips, and a finger carried by said car and operable, as said car approaches said upper station, to enter between said lips, engage said weight beyond its center of gravity, and lift the same over said lips to deposit the same in said car.
